ATTORNEY

UNITED STATES PATENT OFFICE.

GEHARD PETERSON, OF GRAND FORKS, NORTH DAKOTA.

SASH HOLDER AND LOCK.

Application filed May 13, 1921. Serial No. 469,289.

To all whom it may concern:

Be it known that I, GEHARD PETERSON, a citizen of the United States, residing at Grand Forks, in the county of Grand Forks and State of North Dakota, have invented new and useful Improvements in Sash Holders and Locks, of which the following is a specification.

This invention relates to a window sash holder and lock structure applicable for attachment to the strap or bead of a window frame for engagement with the sash of a ¹⁰ slideable window, to hold the window in adjusted positions, and also to lock it in closed ¹⁵ position.

A further object of this invention is to provide a device as specified which will not mar any visible part of a window structure and one which includes a spring actuated ²⁰ wedge arranged to hold a lower sash in raised position and lock it in such position against downward movement.

Other objects of the invention will appear in the following detailed description and ²⁵ in the accompanying drawing wherein:

Fig. 1 is a fragmentary section through a window structure showing the improved sash holder and lock applied.

Fig. 2 is a longitudinal section through ³⁰ the improved sash holder and lock showing the same in an inoperative position.

Fig. 3 is a cross section on the line 3—3 of Fig. 2.

Fig. 4 is a detail section on the line 4—4 ³⁵ of Fig. 2.

Referring more particularly to the drawing the improved sash holder and lock comprises a carrying body or plate 1 which is adapted to be inserted in a suitable recess ⁴⁰ in a window frame, and pinned thereto by means of any suitable type of fastening device which extends through the openings 2 in the body 1. The body 1 is recessed intermediate its ends and it has a locking ⁴⁵ pawl 3 pivotally mounted therein. The locking pawl 3 is provided with a cutout portion 4 which has communication with the pivotal pin receiving opening 5 thereof into which cutout portion 4 a suitable ear ⁵⁰ extends. The locking pawl 3 has a finger tip 6 formed thereon to facilitate its manual operation and when used for locking a window sash as shown at A against movement, the locking pawl 3 is moved by means ⁵⁵ of the finger tip 6 into the recess 7 formed in the sash A. As clearly shown in Fig. 1

of the drawing the lower side of the recess 7 is abrupt so that in an effort to raise the sash A would wedge the pawl and sash together and prevent raising movement of the ⁶⁰ sash.

The holder structure of the device comprises a wedge 10 carried by the body 1. The wedge 10 is substantially pyramidal in shape and has a plurality of teeth 12 on its ⁶⁵ outer surface which are adapted to bite into the window sash A and hold the sash against downward movement. It will be noted that the teeth 12 are inclined to present inclined surfaces to the window sash ⁷⁰ during its upward movement so as to allow the sash to be raised and to bite into the sash upon downward movement of the same. The wedge 10 is arranged with its apex downward and it has a spring carrying rod ⁷⁵ 13 pivotally connected to its base by a pin 14. The spiral spring 15 is coiled about the rod 13 and engages against the body 1 at its upper end and against a washer 15 at its lower end for urging the wedge 10 outwardly into holding position. The body 1 is provided with a guiding portion 16 which prevents lateral movement of the wedge within the body, and the wedge 10 has a ⁸⁰ finger tip 17 formed thereon to permit manual movement of the pawl into a holding position as shown in Fig. 1 of the drawing or into an inoperative position as shown at Fig. 2 of the drawing. When the wedge 10 is moved into an inoperative position its ⁸⁵ apex engages in a notch 18 formed in the body 1 while the inner corner of its base engages the rear of the inner wall of the body 1, positioning the toothed side of the wedge out of position for engagement with ⁹⁰ a window sash and permit the sash to be moved freely.

The finger tips 6 and 17 project out of the recess in which the body 1 is mounted so as to permit manual operation of the sash ⁹⁵ holder and lock.

It is, of course, to be understood that the invention may be constructed in various other manners and the parts associated in different relations and, therefore, I do not ¹⁰⁵ desire to be limited in any manner except as set forth in the claims hereunto appended.

Having thus described my invention what I claim is:

1. In a device as set forth a body, a holder ¹¹⁰ wedge within said body and having a serrated sash engaging surface, a rod pivotally

connected to said wedge and carried by said body, a spring coiled about said rod and adapted to urge said wedge in window supporting position, a finger tab upon said wedge for moving it into and out of operative position, said body provided with a recess adapted to receive a portion of said wedge to hold the wedge in an inoperative position.

10 2. A sash holder and lock comprising in combination with an upper and lower sash,

the latter having the recess formed therein, a plate secured to the upper sash, a pawl pivotally connected to the upper portion of the plate and adapted to be swung into said recess, and a slidably mounted wedge supported by the lower end of the plate adapted to create binding action between the plate and the lower sash.

In testimony whereof I affix my signature.

GEHARD PETERSON.
